AMPLIFICATION OF ELECTRIC OSCILLATIONS

Application filed September 27, 1930. Serial No. 484,728.

This invention relates to amplifying stages of, and similar to the type commonly known as push-pull stages and more particularly to the elimination or minimization of objectionable hum or ripple components in the output of such stages resulting from the excitation by alternating current of the filaments of any tubes employed therein. The invention relates specifically to such stages wherein are employed tubes whose filaments comprise their cathodes; and all tubes hereinafter referred to are intended to be considered as of that type, in distinction to those employing indirectly heated cathodes.

In the use of any stage of amplification, it is necessary to connect the input circuit return, or one side of the input circuit, to the filament system of the tube or tubes employed; and it is the object of my invention to provide a novel method of connection and adjustment of such input circuit return in a stage having a push-pull input circuit and employing a tube or tubes whose filaments are energized by alternating current, characterized by simplicity as well as great effectiveness in the minimization of hum or ripple components in the output of such stage resulting from such alternating current excitation.

In the detailed description of my invention hereinafter set forth, reference is had to the accompanying drawings, of which:

Figure 1 is a diagrammatic view of my invention in one form; and

Figure 2 is a like view thereof in a modified form.

When the filament of a tube is energized by alternating current it is customary to make connection of the input circuit return to a point of intermediate potential with respect to the ends of the filament. If the filament and the extremities of the active portion thereof be respectively symmetrical about the axis of a helical grid, which is a common tube construction, and if the filament be of generally uniform characteristics throughout its active length, such connection may advantageously be made to a point of exact mid-potential with respect to the ends of the active portion of the filament. Such point of connection might then be termed the opti-

mum point, in that connection thereto will reduce to a minimum hum or ripple components in the output of the tube produced by the effect of the alternating current filament energization on the grid and anode potentials applied to the tube, and in particular on such grid potential. Failure of the tube construction or of the filament characteristics to conform to the conditions outlined above may, however, cause the optimum point as defined above to be of other than exact mid-potential with respect to the ends of the filament. Such non-coincidence of the optimum point and the mid-potential point is very common, even in tubes of the symmetrical filament construction outlined above, due to non-uniform characteristics of the filament over its active length.

The principal effect of a connection of the input circuit return to a point other than the optimum point therefor is that of the application to the grid of the tube of an A. C. voltage, cyclic with respect to the filament energizing voltage and of amplitude equal to the potential difference between the point of actual connection and the optimum point. It is common practice to make possible connection of the input circuit return to the optimum point for any tube which may be used in a single tube stage by shunting across the filament terminals of the tube socket a potentiometer, and connecting the input circuit return to the variable contact thereof. For any given tube, adjustment of said variable contact to the optimum point of potential may be effected by observing for minimum ripple in the output of the tube.

This method of obtaining optimum connection of the input circuit return may be applied to a stage employing two tubes or groups of tubes and so arranged that the dynamic grid potentials of one tube or group of tubes is opposite in phase to that of the other tube or group of tubes, such as the usual push-pull amplifying stage. Such application requires the use of separate means for the energization of the filament or filaments of each of the two tubes or groups of tubes from the same original source of alternating current, and two potentiometers each with a

variable contact, one shunted across the terminals of each such filament or filaments. The separate filament energizing means may be two secondary windings on the same transformer, two separate transformers whose primaries are supplied from the same A. C. line, or the like.

I have discovered that in such a stage the arrangement outlined in the preceding paragraph is needlessly complicated, both in composition and employment, and in the stead thereof I employ such separate means for the energization of the filament or filaments of each of the two tubes or groups of tubes, a single potentiometer, with variable contact, shunted across the filament terminals of one of the two tubes or groups of tubes, and a fixed point of connection of intermediate potential with respect to the filament terminals or extremities of the other tube or group of tubes. The variable contact of said potentiometer is connected to said fixed point of connection and thereto is connected the input circuit return. Such fixed point of connection may be a fixed contact or tap on a resistance shunted across the filament terminals of the latter-mentioned tube or group of tubes; it may be a fixed tap on the transformer secondary winding which may be employed for the energization of the filament or filaments of such latter-mentioned tube or group of tubes; or it may be made in any other suitable manner. In operation it is necessary merely to adjust the variable contact of the single potentiometer until minimum ripple is observed in the output of the stage, as by auditory observation of the loud speaker if such is being supplied with energy from the stage.

In Figure 1 I show such a stage incorporating my invention. Transformer T1 is shown as coupling the source of oscillations to be amplified by the stage to the tubes V1 and V2 of the stage, these tubes having cathodes or filaments F1 and F2, grids G1 and G2, and anodes A1 and A2, respectively. Transformer T2, with primary P, is shown as coupling the dynamic output of the stage to a loud speaker, for which, however, may be substituted any other apparatus into which the stage is intended to feed. Sources B and C, of D. C. anode and grid potential, respectively, for tubes V1 and V2 are shown by way of example as batteries. Filaments F1 and F2 are energized separately from secondaries S1 and S2, respectively, of transformer T3, the primary of which is supplied with alternating current by generator H, which is intended to depict any suitable source of alternating current. Across F1 is connected potentiometer N, having variable contact S; and across F2 is connected resistance R, having fixed tap V, located preferably at or near the center of the resistance of R. S and V

are connected together and to the sources B and C of D. C. potentials.

In Figure 2 I show a similar stage, this figure differing from Figure 1 in three respects: first, that resistance R with its tap V has been replaced by a tap W on the secondary winding S2; secondly, that a group of tubes, V1 and V11, with all elements thereof respectively in parallel, have been substituted for the single tube V1 of Figure 1 and a group, V2 and V22, for the single tube V2; and thirdly, that the batteries B and C of Figure 1 have been replaced by a common battery or source of direct current E and by resistance D, for self-biasing of the tubes, as will be understood. Other symbols have similar significances to similar symbols in Figure 1. It will be understood that in the first respect of difference from Figure 1, Figure 2 shows my invention in a modified form; but that in the other respects of difference, Figure 2 merely illustrates alternative arrangements possible with any embodiment of my invention.

The method of adjustment of the circuit of Figure 1 is the movement of the contact S to that position on potentiometer N which results in minimum ripple in the output of the stage, or across the entire primary P of transformer T2. The condition which tends principally to be established by such adjustment is the application to the grid of the tube V1 of an A. C. voltage similar in potential and phase to that which exists between tap V and the optimum point of input circuit return connection for tube V2, or in other words to that which is applied to the grid of tube V2 by virtue of its fixed input circuit return. Since the stage is responsive in dynamic operation to out-of-phase potentials on the grids of the two tubes, the A. C. voltages applied to the grids of the tubes as abovementioned, being in phase with each other, mutually cancel in their effect on the dynamic output, or in the voltage appearing across the entire primary P. When two or more paralleled tubes are used in each half of the stage, as in Figure 2, the method of adjustment and theory of operation are identical with those applying in the case of the use of single tubes in each half, as in Figure 1. It may be observed that a group of paralleled tubes tends to have a single effective optimum point of input circuit return connection, as has a single tube.

There are secondary factors which may call for such a setting of contact S that the A. C. grid potentials abovementioned, though in phase with each other, are slightly different in amplitude. Among these are inequalities in amplification factors or plate impedances of the two tubes or groups of paralleled tubes; inexact center-tapping of primary P; effect on anode potential of non-coincidence of actual input circuit return point and optimum

point, and the like. These factors are, in whole or large part, automatically taken care of in adjustment of contact S for minimum ripple voltage across primary P; but in almost 5 no case do they influence such adjustment in more than a very minor degree, the grid voltage considerations outlined above remaining the principal determinant of the proper position of contact S for any given tubes or groups 10 of tubes.

If for special purposes the dynamic output circuit of either tube or group of tubes be reversed in connection, my invention may be used in form and manner of adjustment as 15 disclosed above, but actually the contact S of potentiometer N will be so adjusted that the A. C. voltages caused to appear at the two grids will be out of phase with respect to each other. Such and other modifications, it will 20 be understood, may be made in the choice and disposition of components and in manner of adjustment and theoretical operation without departing from the spirit or scope of my invention, as hereinabove or in the appended 25 claims disclosed.

I claim:—

1. In a system for the amplification of electric oscillations, in combination, two vacuum tubes each having at least an anode, a grid, 30 and a filament comprising a cathode; an input circuit for simultaneously supplying oscillations to be amplified to each of said tubes, in substantially equal amplitudes but in opposite phase, said input circuit including means 35 for rendering the grids of said tubes negative with respect to their filaments; a circuit connected to the output of said tubes to receive oscillations therefrom; means for supplying anode current to said tubes; separate means 40 for energizing the filament of each of said tubes from a common source of alternating current; a connection from said input circuit to a point of non-adjustable intermediate potential with respect to the extremities of the 45 filament of one of said tubes; and a connection from said input circuit to a point the potential of which may be varied over at least a portion of the range of potential between the 50 extremities of the filament of the other of said tubes.

2. In a system for the amplification of electric oscillations, in combination, two vacuum tubes each having at least an anode, a grid, 55 and a filament comprising a cathode; an input circuit for simultaneously supplying oscillations to be amplified to each of said tubes, in substantially equal amplitudes but in opposite phase, said input circuit including 60 means for rendering the grids of said tubes negative with respect to their filaments; a circuit connected to the output of said tubes to receive oscillations therefrom; means for supplying anode current to said tubes; separate 65 means for energizing the filament of each of said tubes from a common source of alter-

nating current; a fixed tap on said means for energizing the filament of one of said tubes; a potentiometer comprising a resistance element shunted across the extremities of the filament of the other of said tubes and a 70 contact whose position on said resistance element may be varied; and a connection from said tap and said contact to said input circuit.

3. In a system for the amplification of electric oscillations, in combination, two vacuum tubes each having at least an anode, a grid, 75 and a filament comprising a cathode; an input circuit for simultaneously supplying oscillations to be amplified to each of said tubes, in substantially equal amplitudes but in opposite phase, said input circuit including means for rendering the grids of said tubes negative with respect to their filaments; a circuit connected to the output of said tubes to receive oscillations therefrom; means for supplying anode current to said tubes; separate 80 means for energizing the filament of each of said tubes from a common source of alternating current; resistance shunted across the extremities of the filament of one of said tubes, said resistance comprising two resistance sections in series, with a fixed contact between said sections; a potentiometer comprising a resistance element shunted across the extremities of the filament of the other 85 of said tubes and a contact whose position on said resistance element may be varied; and a connection from each of said contacts to said input circuit.

4. In a system for the amplification of electric oscillations, in combination, a plurality of vacuum tubes each having at least an anode, a grid, and a filament comprising a cathode, said tubes being arranged in two groups, similar elements of the tubes in each group being connected in parallel; an input circuit for simultaneously supplying oscillations to be amplified to each of said groups of tubes, in substantially equal amplitudes but in opposite phase, said input circuit including means for rendering the grids of said tubes negative with respect to their filaments; a circuit connected to the output of said tubes to receive oscillations therefrom; means for supplying anode current to said tubes; separate 100 means for energizing the filaments of each of said groups of tubes from a common source of alternating current; a connection from said input circuit to a point of non-adjustable intermediate potential with respect to the extremities of the filaments of one of said groups of tubes; and a connection from said input circuit to a point the potential of which may be varied over at least a portion of the range of potential between the extremities of the filaments of the other of said groups of tubes.

5. In a system for the amplification of electric oscillations, in combination, a plurality of vacuum tubes each having at least

an anode, a grid, and a filament comprising a cathode, said tubes being arranged in two groups, similar elements of the tubes in each group being connected in parallel; an input circuit for simultaneously supplying oscillations to be amplified to each of said groups of tubes, in substantially equal amplitudes but in opposite phase, said input circuit including means for rendering the grids of said tubes negative with respect to their filaments; a circuit connected to the output of said tubes to receive oscillations therefrom; means for supplying anode current to said tubes; separate means for energizing the filaments of each of said groups of tubes from a common source of alternating current; a fixed tap on said means for energizing the filaments of one of said groups of tubes; a potentiometer comprising a resistance element shunted across the extremities of the filaments of the other of said groups of tubes and a contact whose position on said resistance element may be varied; and a connection from said tap and said contact to said input circuit.

6. In a system for the amplification of electric oscillations, in combination, a plurality of vacuum tubes each having at least an anode, a grid, and a filament comprising a cathode, said tubes being arranged in two groups, similar elements of the tubes in each group being connected in parallel; an input circuit for simultaneously supplying oscillations to be amplified to each of said groups of tubes, in substantially equal amplitudes but in opposite phase, said input circuit including means for rendering the grids of said tubes negative with respect to their filaments; a circuit connected to the output of said tubes to receive oscillations therefrom; means for supplying anode current to said tubes; separate means for energizing the filaments of each of said groups of tubes from a common source of alternating current; resistance shunted across the extremities of the filaments of one of said groups of tubes, said resistance comprising two resistance sections in series, with a fixed contact between said sections; a potentiometer comprising a resistance element shunted across the extremities of the filaments of the other of said groups of tubes and a contact whose position on said resistance element may be varied; and a connection from each of said contacts to said input circuit.

7. The method of minimizing ripple currents in the output of an amplifying stage having a push-pull input circuit and employing two vacuum tubes whose filaments comprise their cathodes and are energized by alternating current, which consists in separately energizing each of said filaments from a common source of alternating current; in non-adjustably returning said input circuit to the filament system of one of said tubes;

and in so maintaining the point of return of said input circuit to the filament system of the other of said tubes as to cause said tubes to produce substantially equal and opposite ripple currents in said output.

8. The method of minimizing ripple currents in the output of an amplifying stage having a push-pull input circuit and employing two groups of paralleled vacuum tubes whose filaments comprise their cathodes and are energized by alternating current, which consists in separately energizing the paralleled filaments of each of said groups of tubes from a common source of alternating current; in non-adjustably returning said input circuit to the filament system of one of said groups of tubes; and in so maintaining the point of return of said input circuit to the filament system of the other of said groups of tubes as to cause said groups of tubes to produce substantially equal and opposite ripple currents in said output.

This specification signed this 26th day of September, 1930.
